UNITED STATES PATENT OFFICE

128,085

DESIGN FOR A HAIR WAVE PROTECTOR

Emma L. Rueger, Piedmont, Calif.

Application May 20, 1940, Serial No. 92,475

Term of patent 7 years

To all whom it may concern:

Be it known that I, Emma L. Rueger, a citizen of the United States and a resident of Piedmont, county of Alameda, State of California, have invented a new, original, and ornamental Design for a Hair Wave Protector, of which the following is a specification, reference being had to the accompanying drawing, forming part thereof.

I claim:

The ornamental design for a hair wave protector, substantially as shown.

EMMA L. RUEGER.
